ERNEST DAVIS, OF SYRACUSE, NEW YORK, ASSIGNOR TO THE PROSPERITY COMPANY INC., OF SYRACUSE, NEW YORK, A CORPORATION OF NEW YORK

AIR FLOW WITH AUTOMATIC PRESSURE REGULATION

Application filed September 2, 1930. Serial No. 479,811.

This invention relates to pressing machines as garment or laundry presses.

The principal object of the invention is to provide a pressing machine which may be closed under pressure, and which is provided with means for blowing air through one of the pressing elements and means for reducing the pressure between the pressing elements when the air blowing means are operated.

A further object of the invention is to provide a pressing machine having a motor for closing the press under initial light pressure, and a second motor for closing the press under final heavy pressure, and having means for blowing air through one of the pressing elements and for rendering the second motor inoperative when the air blowing means is set in operation.

A further object of the invention is to provide a pressing machine, having a two-step operation, with means for blowing air through one of the pressing elements and for automatically returning the press operating means to the first degree of pressure when the means for blowing air are operated.

Other objects and advantages will appear and will be pointed out as the description proceeds.

The invention consists in the novel features and in the combinations and constructions hereinafter set forth and claimed.

In describing this invention, reference is had to the accompanying drawings in which like characters designate corresponding parts in all the views.

Figure 1 is a side elevation of a garment or ironing machine to which the invention has been applied. Various parts have been carried outside of the normal press structure in order that the structure may be more clearly shown, diagrammatically.

Figure 2 is a diagrammatic view, mostly in section, showing the operating and control mechanism by which the garment or ironing press is operated and by means of which the flow of air through one of the pressing jaws is controlled.

The invention is designed primarily for

use with pressing machines of the type shown in Figure 1 in which a pressing head 10 is secured to a yoke 11 which is mounted at 12 on an upstanding portion of a pressing machine frame 13. The pressing head 10 moves into and out of contact with a fixed pressing element or buck 14 mounted on a support 15 which is secured to the pressing machine frame 13.

A bell crank 20 is pivotally mounted at 21 on the pressing machine frame 13. The bell crank 20 is rocked about its pivot point 21 by a fluid motor 23 which is pivotally connected at 24 to the pressing machine frame 13. A piston rod 25, of the fluid motor 23, is pivotally connected at 26 to the forwardly extending arm of the bell crank 20. The bell crank 20 is pivotally connected at the end of its upwardly extending arm at 28 to a link 30 which is pivotally connected at 31 to the yoke 11.

The link 30 and upstanding arm of the bell crank 20 form a toggle and the fluid motor 23 rocks the bell crank 20 in a counter-clockwise direction in Figure 1, to straighten the toggle to apply final heavy pressure to the pressing elements 10 and 14. An arm 35 formed on the upper end of the link 20 is pivotally connected at 36 to a piston rod 37 of a fluid motor 40. The fluid motor 40 is pivotally connected at 41 to the pressing machine frame 13. The fluid motor 40 is operated to bring the pressing elements together under initial light pressure. Springs 44 and 45 are connected to the pressing machine frame 13 and to the bell crank 20 and yoke 11 respectively to move the press into open position when the pressure in the fluid motors 23 and 40 is released.

The mechanism thus far described is of the conventional type and forms no part per se of the present invention.

Operating mechanism for light pressure

Means are provided to close the press under initial light pressure and such means preferably include a pedal 50 formed on the end of a foot operated lever 51 which is pivoted at 52 to the pressing machine frame 13. An operating link 54 is pivotally connected at 55

95

100

to the foot operated lever 51. A spring 56 is interposed between a cross member 49 of the pressing machine frame 13 and a collar 57 which is rigidly secured to the operating link 54. This spring 56 normally holds the operating link 54 down and moves the foot operated lever 51 until an adjustable stop such as a set screw 59, mounted in the foot operated lever 51, contacts with a stop 60. When the 10 pedal 50 is moved downwardly the spring 56 will be compressed and a latch member 62, which is pivotally mounted at 63 on the foot operated lever 51, contacts with the latch 64 to hold the pedal 50 down against the tension 15 of the spring 56.

The operating link 54 transmits motion of the foot operated lever 51 to a bell crank 66 which is pivotally mounted at 67 on a bracket 68 formed adjacent to valve casings 70 and 20 71. The valve casing 71 contains a normally closed intake valve 72 and a normally open exhaust valve 73 which are secured together by a spacer rod 74 so that they operate as a unit. A spring 75 holds the valves 72 and 25 73 in normal position.

The valve casing 70 contains a normally open exhaust valve 77. The exhaust valves 73 and 77 are provided with valve stems which extend through the ends of the valve 30 casings 71 and 70 respectively, and a cross member 80, which is mounted on the bell crank 66, operates against these valve stems to close the exhaust valves 73 and 77 and open the intake valve 72 when the pedal 50 is depressed.

35 The purpose of the exhaust valve 77 is to require the closing of the press under initial light pressure before the application of final heavy pressure as will be more fully explained hereinafter.

40 When the pedal 50 is depressed to operate the valves in the valve casings 70 and 71, working fluid such as air will flow from a fluid supply line 82, around the open intake valve 72, through the valve casing 71, and 45 through a conduit 84, to the fluid motor 40. The fluid motor 40 includes a cylinder 85 having a piston 86 therein which is rigidly secured to the piston rod 37. When working fluid is supplied through the conduit 84 to 50 the cylinder 85 of the fluid motor 40, the piston 86 and piston rod 37 will be moved upwardly to actuate the yoke 11 to bring the pressing head 10 into, or substantially into, contact with the buck 14. If the operator does 55 not remove his hands from the buck 14 before the fluid motor 40 closes the press, no injury will result since the pressure exerted by the fluid motor 40 on the pressing head 10 is not sufficient to cause injury.

60 *Operating mechanism for final heavy pressure*

Final heavy pressure is applied by operating the fluid motor 23 and the control means 65 for operating this motor are of the two-hand

control type so that it is necessary for the operator to remove both hands from between the pressing elements before final heavy pressure can be applied. The two-hand control mechanism includes a valve casing 90 which contains a check valve 91 through which air may pass from the valve casing 90, but which will prevent back flow of air into the valve casing 90. A spring 92 holds the check valve 91 in normal closed position. The valve casing 90 also contains an exhaust valve 93 having a stem 94 which projects through the end of the valve casing 90 and against which a handle 95 operates to close the exhaust valve 93. A spring 96 normally holds the handle 95 in position so that the exhaust valve 93 may remain open.

The second valve casing of the two-hand control means is indicated as 98 and contains a normally closed intake valve 99, and a normally open exhaust valve 100 which are secured to a spacer rod 101 so that they operate as a unit. A spring 103 holds the valves 99 and 100 in normal position. The exhaust valve 100 is provided with a valve stem 104 which projects through the end of the valve casing 98 and a handle 105 operates against the end of the valve stem 104 to move the valves 99 and 100 into operated position. A spring 106 normally holds the handle 105 in position so that the valves 99 and 100 may remain in normal position under influence of the spring 103.

Working fluid from the fluid supply line 82 passes through a conduit 110, to the valve casing 98 and when the handle 95 is moved to open the intake valve 99 and close the exhaust valve 100, working fluid will flow from the pipe 110, around the open intake valve 99, through the valve casing 98, and through a conduit 112 which connects the valve casing 98 with the valve casing 90. Unless the handle 95 has been operated to close the exhaust valve 98, working fluid from the pipe 112 will exhaust past the open exhaust valve 93. Thus, it is necessary that both handles 95 and 105 be operated if the fluid motor 23 is to be operated. If the exhaust valve 93 is closed, working fluid from the pipe 112 may pass through the valve casing 90, around the check valve 91, and through a pipe 114 to the diaphragm chamber 115 to operate a diaphragm 116 which is located in the diaphragm chamber 115.

The diaphragm 116 operates a plunger 117 which projects through the end of the casing 115 into contact with a rocker arm 120. The diaphragm chamber 115 is formed as a part of a valve casing 122 and a duct 123 connects the pressure side of the diaphragm casing 115 with the interior of the valve casing 122. The valve casing 122 contains a normally closed intake valve 125 and a normally open exhaust valve 126 which are joined together by a spacer rod 128 so that they operate as

a unit. A spring 129 holds the valves 125 and 126 in normal position. The exhaust valve 126 is provided with a valve stem 130 with which the rocker arm 120 contacts to operate the valves 125 and 126 in the valve casing 122 when pressure is supplied through the pipe 114 to the diaphragm chamber 115.

A pressure regulating or reducing valve 140 is connected by a pipe 141 with the pipe 110. A valve head 143 is mounted in the casing of the pressure regulating valve 140 and a valve stem 144 is connected to a diaphragm 145 which is normally held in position by a spring 146 so that the valve 143 is normally open to permit air to pass from the pipe 141 and through the valve casing 140. When the pressure reaches a predetermined amount the diaphragm 145 will be moved upwardly against the tension of the spring 146 and the valve head 143 will be closed and will cut off the flow of air through the pressure regulating valve 140. When the pressure drops, the spring 146 will move back the diaphragm 145 to again open the valve 143. Screw means 148 are provided to adjust the tension of the spring 146 and thus regulate the pressure of the air which can pass through the pressure regulating valve 140.

The operating handle 105 should be depressed and quickly released so that the intake valve 99 will be opened for a moment only. A momentary charge of air is sufficient to operate the diaphragm 116 and thereafter the handles 95 and 105 may be released. If the handles 95 and 105 are held down for a longer period, air at supply pressure would be admitted into the high pressure cylinder 154 through the duct 123, whereby the motor would apply a greater pressure between the press jaws than would be expected because of the pressure regulating valve 140.

The discharge side of the pressure regulating valve 140 is connected by a pipe 150 with the intake end of the valve casing 122. When the valves 125 and 126 in the valve casing 122 are in operative position, working fluid from the pressure regulating valve 140 will flow through the pipe 150, around the open intake valve 125, and through a pipe 151, to the pipe 152 which supplies working fluid to the fluid motor 23. The fluid motor 23 includes a cylinder 154 having a piston 155 therein which is rigidly secured to the piston rod 25. When working fluid is thus supplied to the cylinder 154, the piston 155 and piston rod 25 will move downwardly to operate the bell crank 20, link 30, and yoke 11, to apply final heavy pressure to the pressing elements. It should be noted that working fluid supplied through the pipe 151 to the pipe 152 will exhaust through a pipe 160 unless the exhaust valve 77 in the valve casing 70 has previously been closed by operation of the pedal 50 which controls the clos-

ing of the press under initial light pressure. It is necessary therefore, that the operator depress the pedal 50 to close the press before applying final heavy pressure with the control handles 95 and 105.

70

Air blowing means

Means are provided for blowing air through one of the pressing elements such as the buck 14, which is constructed with an air blowing chamber 165 covered by a perforated plate 166. This construction of the buck is conventional and air is supplied to the chamber 165 through a pipe 168. Valve means, such as a poppet valve 170 in the top of the pipe 168, are provided to control the flow of air through the pipe 168. The valve 170 has a long stem 172 which projects downwardly through the pipe 168 and through the branch connection 174 and a suitable stuffing box 175. A collar portion 176 is formed on the lower end of the valve stem 172 and a spring 177, located between the collar portion 176 and the stuffing box 175, normally holds the valve 170 closed.

75

A bracket 180 is secured below the branch connection 174 and supports a diaphragm chamber 182 which contains a diaphragm 183. A plunger 185 extends through the top of the diaphragm chamber 182 and contacts with the collar portion 176 of the valve stem 172. When pressure is supplied to the diaphragm chamber 182, the diaphragm 183 will be moved upwardly to raise the plunger 185 and valve stem 172, against the tension of the spring 177 to open the valve 170.

80

The supply of working fluid to the diaphragm chamber 182 to operate the diaphragm 183 is controlled by a handle 188. This handle 188 operates the valves in a valve casing 190 which contains a normally closed intake valve 191 and a normally open exhaust valve 192. The valves 191 and 192 are joined by a spacer rod 193 so that they operate as a unit. A spring 194 holds the valves 191 and 192 in normal position. The valve 192 is provided with a valve stem 195 which projects through the end of the valve casing 190. A rocker arm 197 is rigidly connected to the handle 188 and is pivoted on the valve casing 190 and movable into engagement with the valve stem 195 to move the same to operate the valves 190 and 192.

85

A diaphragm chamber 198 is located in the lower part of the valve casing 190 and contains a diaphragm 199 which operates a plunger 200. The plunger 200 extends through the front end of the diaphragm chamber 198 and contacts with an abutment screw 202 mounted on the rocker arm 197. A duct 205 connects the interior of the valve casing 190, at a point between the valves 191 and 192, with the diaphragm chamber 198 and working fluid is supplied through this duct 205 to operate the diaphragm 199.

90

95

100

105

110

115

120

125

130

to move the plunger 200 and lock the rocker arm 197 and valves 191 and 192 in operated position. Working fluid is supplied to the valve casing 190 through a pipe 207 which connects with the pipe 84. The valve casing 190 is connected at a point midway between the valves 191 and 192, by a pipe 208 to the diaphragm chamber 182.

When the handle 188 is raised the valves 10 in the valve casing 190 will be operated to open the intake valve 191 and close the exhaust valve 192. If the press has been closed under initial light pressure and the pipe 84 is therefore in communication with the fluid 15 supply line 82, working fluid will flow from the pipe 84, through the pipe 207, around the open intake valve 191, through the valve casing 190, and through the pipe 208, to the diaphragm chamber 182 to operate the dia- 20 phragm 183 therein and raise the plunger 185 and valve stem 172 to open the valve 170. When the valve 170 is open air from the blower 210 will pass through the pipe 212, branch connection 174, and pipe 168, to the 25 air blowing chamber 165 from which it will pass through the perforated plate 166 and through the work on the buck.

The pipe 212 may be connected to either the suction or discharge side of the blower 30 210 so that the blower 210 will supply air to the chamber 165, or withdraw air from the chamber. When air is withdrawn from the chamber 165 air will blow downwardly through the perforated plate 166. When air 35 is supplied to the chamber 165 air will blow upwardly through the perforated plate 166. Both modes of operation are well-known in the art and it is of no importance which method is used with the automatic operating mechanism of this invention.

Since it is impossible to effectively blow air when the pressing elements are together under heavy pressure, time may be saved by providing means to automatically place the 45 pressing elements under light pressure when the control means for blowing air are operated, and this means includes a cylinder 220 having a piston 222 therein. A piston rod 225 is rigidly connected to the piston 222 which projects through the cylinder 220 so that its end contacts with the rocker arm 120 when the piston 222 is operated. A pipe 230 connects the cylinder 220 with the pipe 208 and when the control handle 188 is operated 50 to supply working fluid through the pipe 208 to the diaphragm chamber 182, working fluid will also be supplied to the cylinder 220. When working fluid is supplied to the cylinder 220 the piston 222 and piston rod 225 will be moved to bring the end portion 55 226 into contact with the rocker arm 120 to move the rocker arm into inoperative position, against the pressure of the diaphragm 116, and permit the spring 129 to restore the valves 125 and 126 to normal position. When

the valve 126 is opened, working fluid from the fluid motor 23 will escape through pipes 152 and 151, valve casing 122, and past the open exhaust valve 126. Since the fluid motor 23 applies final heavy pressure to the 70 pressing elements, the opening of the exhaust valve 126 automatically renders the fluid motor 23 inoperative and restores the pressing elements to a condition of light 75 pressure.

A pressure gauge 240 may be connected by a pipe 245 with the pipe 152 to indicate the pressure of the working fluid in the cylinder 154 of the fluid motor 23. If this pressure is not correct the pressure regulating valve 140 80 may be adjusted by means of the screw 148.

Operation of machine

The machine is initially closed under light pressure by depressing the pedal 50 which 85 closes the exhaust valves 73 and 77 and opens the intake valve 72. The latch member 62 cooperates with the latch 64 to hold the pedal 50 in operated position. Working fluid from the fluid supply line 82 will flow around the 90 open intake valve 72, through the valve casing 71 and pipe 84 to the cylinder 85 to operate the fluid motor 40 and bring the pressing 95 elements together under initial light pressure.

Heavy pressure is applied by actuating the handles 95 and 105. Operation of the handle 105 opens the intake valve 99 and permits working fluid to flow from the fluid supply 100 line 82 through the pipe 110, around the open intake valve 99, through the valve casing 98, pipe 112, valve casing 90, past the check valve 91, and through the pipe 114, to the dia- 105 phragm chamber 115. This supply of working fluid to the diaphragm chamber 115 operates the diaphragm 116 to move the plunger 117 and rocker arm 120 to open the valve 125 and close the valve 126 in the valve casing 122. The opening of the intake valve 125 permits working fluid to flow from the 110 pressure regulating valve 140, around the open intake valve 125, through valve casing 122, and through the pipes 151 and 152 to the cylinder 154 to operate the fluid motor 23 and apply final heavy pressure to the pressing 115 elements.

The press may be opened without making use of the air blowing means. If the operator releases the latch member 62 the spring 56 will restore the foot operated lever 51 to normal position and permit the exhaust valves 73 and 77 to open. Working fluid from the fluid motor 23 will then exhaust through the pipe 152, pipe 160, and valve casing 70 past the open exhaust valve 77. Working fluid from the fluid motor 40 will exhaust through the pipe 84, and valve casing 70 past the open exhaust valve 73. The supply of working fluid to the fluid motor 40 will be cut off when the exhaust valve 73 opens since the 120 125 130

- intake valve 72 is rigidly connected by spacer rod 74 to the exhaust valve 73 and closes when the exhaust valve 73 opens. Fluid supply to the fluid motor 23 will be cut off when the 5 exhaust valve 77 is opened and the pressure in the pipes 151, 152 and 160 drops. A drop in the pressure in the pipe 151 will cause a reduction in the pressure in the valve casing 122 and working fluid in the diaphragm 10 chamber 115 will escape through the duct 123, thus reducing the pressure behind the diaphragm 116 and permitting the spring 129 to move the intake valve 125 into closed position. The closing of the intake valve 125 15 will open the exhaust valve 126 to which it is rigidly connected by the spacer rod 128 and the open exhaust valve 126 will provide another means for escape of working fluid from the fluid motor 23.
- 20 If the operator wishes to blow air he will move the handle 188 to operate the valves in the valve casing 190 and open the intake valve 191. Working fluid from the pipe 84 will flow through the pipe 207, around the 25 open intake valve 191, through the valve casing 190, and pipe 208, to the diaphragm chamber 182 to operate the diaphragm 183 therein and open the valve 170, as previously described. When the valve 170 is opened 30 air may blow through the pipe 212, branch connection 174, pipe 168, air blowing chamber 165, and perforated plate 166 on which the padding of the buck is supported. When 35 the handle 188 is operated to supply working fluid through the pipe 208 to the diaphragm chamber 182, working fluid will also be supplied through the pipe 230 to the cylinder 220 and the piston 222 and piston rod 225 will be operated to move the rocker arm 40 120 away from the valve stem 130 and permit the spring 129 to restore the valves 125 and 126 to normal open press position. The closing of the intake valve 125 cuts off the supply of working fluid to the fluid motor 45 23 and the opening of the exhaust valve 126 permits working fluid to escape from the fluid motor 23, thus rendering the fluid motor 23 inoperative and restoring the pressing elements to a condition of light pressure.
- 50 After the air blowing operation, the operator may open the press by releasing the latch member 62, as previously described. From the foregoing description it will be apparent that I have devised a pressing machine having air blowing means and means for automatically operating the control mechanism so that the pressing elements will be closed under initial pressure only when the air blowing means go into operation.
- 55 The invention is illustrated in its preferred embodiment but various changes and modifications may be made without departing from the spirit of the invention as set forth in the appended claims.
- 60 What I claim is:
1. In a pressing machine in combination cooperating pressing elements one of which is movable with respect to the other; press operating mechanism to actuate the movable pressing element and operable to successively close the press under an initial light degree of pressure and a final heavy pressure; means for causing a current of air to pass through one of the pressing elements; and heavy pressure release means operated by 70 operation of the air current causing means to reduce the pressure exerted by the press operating mechanism to the initial light pressure.
2. In a pressing machine in combination cooperating pressing elements one of which is movable with respect to the other; press operating mechanism to actuate the movable pressing element including first motor means for closing the press under initial 80 light pressure, and second motor means for closing the press under final heavy pressure; means for causing a current of air to pass through one of the pressing elements; release means to render the second motor 85 means inoperative to apply pressure to the pressing elements; and connections between the air current causing means and the release means so that operation of said air current causing means will operate said release 90 means.
3. In a pressing machine in combination cooperating pressing elements one of which is movable with respect to the other; press operating mechanism to actuate the movable pressing element including motor means; means for causing a current of air to pass through one of the pressing elements; and means controlled by the air current causing 95 means to cut off the supply of working fluid to the motor means and exhaust working fluid from the motor means.
4. In a pressing machine in combination cooperating pressing elements one of which is movable with respect to the other; press operating mechanism to actuate the movable pressing element including a fluid motor; valve means to control the flow of working fluid to and from the motor; means for causing a current of air to pass through one of the pressing elements; and motor means operated by the pressure caused by the air current to operate the valve means to cut off the supply of working fluid to the motor and to 100 open an exhaust for working fluid from the 105 motor.
5. In a pressing machine in combination cooperating pressing elements one of which is movable with respect to the other; press operating mechanism to actuate the movable pressing element including a first fluid motor to close the press under initial light pressure; a second fluid motor to close the press under final heavy pressure; valve means to control the flow of working fluid to 110 115 120 125 130

- the motors; means for causing a current of air to pass through one of the pressing elements; and means controlled by the air current means to operate the valve means to cut off the supply of working fluid to the second fluid motor and open an exhaust for working fluid from said second fluid motor so as to decrease the pressure between the pressing elements.
- 10 6. In a pressing machine in combination cooperating pressing elements one of which is movable with respect to the other; press operating mechanism to actuate the movable pressing element including motor means; means for causing a current of air to pass through one of the pressing elements; control devices for the air current means including a valve and an air conduit; control means for the motor means; and mechanism operated by air pressure in said air conduit for operating the control means of the motor means to reduce the pressure exerted by the motor means on the pressing elements.
- 15 7. In a pressing machine in combination cooperating pressing elements one of which is movable with respect to the other; operating mechanism to actuate the movable pressing element including a motor for applying heavy pressure to the pressing elements; valve means for controlling the flow of working fluid to and from the motor; means for blowing air through one of the pressing elements; and pressure operated mechanism associated with the valve means and operated by air pressure from the air blowing means,
- 20 when the same are operated to blow air, to actuate the valve means to cut off the supply of working fluid to the motor and open an exhaust for working fluid from the motor so that the motor becomes inoperative to apply pressure to the pressing elements.
- 25 8. In a pressing machine in combination cooperating pressing elements, one of which is movable with respect to the other; operating mechanism to actuate the movable pressing element including first motor means for closing the press under initial light pressure, and second motor means for closing the press under final heavy pressure; valve means to control the supply of working fluid to the first motor means; other valve means to control the flow of working fluid to and from the second motor means; and means for locking said other valve means in operated position in which working fluid is prevented from exhausting from the second motor means; means for causing a current of air to pass through one of the pressing elements; and a third motor means connected with the air current means and operated by the pressure therein for releasing the locking means so that said other valve means will cut off the flow of working fluid to the second motor means and permit working fluid to exhaust therefrom.
- 30 In testimony whereof, I have hereunto signed my name, at Syracuse, in the county of Onondaga, and State of New York, this 29th day of August, 1930.
- 35 ERNEST DAVIS.
